RESILIENT SOCKET

Daniel I. Reiter, New York, N. Y.

Application October 15, 1945, Serial No. 622,363

7 Claims. (Cl. 24—216)

1

This invention relates to resilient snap fastener sockets and particularly to the type designed for application to articles of leather, heavy fabric or the like such as pocket books, gloves and similar goods.

My invention contemplates the provision of a resilient socket adapted to be made of thin metal but, by the provision of double thicknesses of material where needed, being given adequate strength against distortion under unusual stresses including the stresses developed in assembling the parts, the socket being made preferably of two members so bent and formed as to provide mutual reinforcement of the members at the proper places.

My invention further contemplates the provision of a strong durable resilient socket readily applicable to leather goods and adapted for economical manufacture and assembly and having a stud entrance opening not likely to injure the stud or to wear out and permitting the stud to be easily inserted thereinto.

The various objects of the invention will be clear from the description which follows and from the drawings, in which

Fig. 1 is a partial vertical section and partial elevational view of the socket as it appears assembled to a sheet and with its cooperating stud in place.

Fig. 2 is a bottom plan view of the same with the stud and the sheets carrying the fastener omitted.

Fig. 3 is a top plan view of the socket as it appears before it is assembled to its holding cap and showing in dash-dot lines how the top part of the socket eyelet is spread when it is clinched to the holding cap.

Fig. 4 is a combined vertical section and front elevation of the same.

Fig. 5 is a fragmentary vertical section of a modified form of the socket before its assembly to the cap.

Fig. 6 is a similar view of another modified form of the socket showing the stud in place.

Fig. 7 is a similar view of still another modified form of the socket.

In the practical embodiment of the invention shown by way of example in Figs. 1 and 2, the sheet of leather, heavy fabric or the like 10 carries the non-resilient stud 11 in the usual manner, the stud being provided with a neck 12 for the reception of the open resilient wire ring 13 of the socket after the head of the stud has been forced past the ring, all in a manner which is well understood.

To form the annular ring-holding groove or recess 14, I prefer to provide a socket made of two members 15 and 16 of comparatively thin metal so formed as to assure the arrangement of two thicknesses of metal at the areas where the socket might tend to fail under stresses put thereon such as during the operation of clinching the socket eyelet portion 17 to its holding cap 18, or if the article in which the socket is used is dropped or stepped on. Below the eyelet 17, the member 15 is enlarged in diameter thereby forming the upstanding cylindrical wall 19 and the substantially flat annular shoulder 20 extending outwardly from the wall a distance slightly greater than half the thickness of the ring, and serving as the top wall of the ring-holding recess 14. The height of the wall 19 is slightly greater than the ring thickness, and at the lower end of said wall is arranged the outstanding substantially flat flange 21 forming part of the base of the socket and to which is secured the corresponding base portion of the member 16 as by bending or rolling over thereon the peripheral rim 22.

The annular flange 23 extending inwardly from the rim 22 forms the base of the member 16 and stiffens and reinforces the flange 21 and together therewith form the base of the socket, said socket base being arranged on one side of the sheet of material 24. The flange 23 is continued inwardly past the wall 19 about half the thickness of the ring to a point substantially directly below the eyelet 17 and at said point is doubled outwardly on itself as at the bend 25 up to the wall 19 to provide the double thickness of metal forming the bottom wall of the ring-holding recess. At said wall 19, the member 16 is bent upwardly into contact with said wall to form the upright outer cylindrical wall 26 of the ring-holding recess and to provide the double thickness of metal shown in Figs. 1 and 4 as a mutual reinforcement of the walls 19 and 26. The uppermost end of the wall 26 being in contact with the shoulder 20, it reinforces said shoulder against possibility of sagging when the socket is assembled, while the shoulder 20 in turn braces the wall 26 against the pressure of an entering stud.

It will be noted that by the provision of the bend 25, the entrance opening 27 for the stud into the interior of the members, is surrounded by a rounded edge, thereby avoiding marring or wear of the stud which might otherwise occur after repeated use. It will be further noted that two thicknesses of metal are used throughout the base and the major part of the ring-holding recess thereby insuring the retention of the critical

accurate dimensions required for proper operation of the socket by the strengthening and reinforcement of the parts where needed, while permitting comparatively thin metal to be employed with resulting economy.

The attaching or eyelet part 17 of the socket need not and should not be made of more than one thickness, since it is intended that said part be deformed by spreading during assembly of the socket. Said eyelet 17 is passed through a suitable opening 28 in the sheet 24 and into contact with the anvil portion 29 of the cap 18 when the socket is to be assembled, the cap being arranged on that side of the sheet 24 opposite to that on which the base is arranged. With the parts in the positions described, the cap and socket are forced toward each other and against the sheet 24, whereby the upper end of the eyelet is spread by the anvil portion 29 of the cap into the position shown in Fig. 1 and in dash-dot lines in Figs. 3 and 4 to distort the upper end of the eyelet and to clinch the socket to the cap with the sheet 24 therebetween.

To insure proper spreading of the eyelet without such pressure on the socket as might distort the ring-holding recess or the stud entrance opening, the spreadable upper portion of the eyelet may be corrugated, grooved or scored as along the upright or longitudinal lines 30 to form lines of weakness along which the eyelet may split or rupture if the spreading force stretches the eyelet beyond its elastic limit.

In the form of the invention shown in Fig. 6, not only is a flared entrance opening 31 provided for the easy insertion thereinto of the stud 11 and for guiding the stud into place, but the height of the eyelet portion 32 is reduced by arranging the flanges 33 and 34 of the socket base so that the flanges form a conical surface tapering upwardly and inwardly from the rim 35. This arrangement also permits the sheets 36 and 37 carrying the socket and stud respectively to be brought quite closely together in the fastened positions thereof.

As shown in Fig. 5, the base 40 of the socket may taper in the opposite direction from that shown in Fig. 6, that is, downwardly and inwardly from the rim 41. Such arrangement of the base is advantageous in those cases where the sheet 42 is thinner than usual, in that the gap which might otherwise appear between the base and the sheet is avoided. In Fig. 5 is also shown a modified form 43 of the socket piece 16 previously described. To further reinforce the shoulder 20 in this form of the invention, a lip or flange 44 is turned inwardly from the top of the upright wall 45, said lip forming the top wall of the ring-holding recess 46 and taking, through the pressure of the ring thereagainst, the major part of the stress incident to the upward movement of the stud into the socket. It will be understood without further illustration or description that such lip may be provided at the upper end of the wall 19 of Figs. 1, 4 and 6 if desired as will now be obvious.

In the form of the invention shown in Fig. 7, the socket member 50 is provided with the ring-holding shoulder 51 at the lower part of the eyelet 52, but the wall 19 is eliminated and replaced by the base flange 53 tapering downwardly and outwardly from the shoulder to form a conical part which terminates in a flat peripheral portion 54. The other socket member 55 differs from the members 16 and 43 in that an outwardly turned lip 56 is provided thereon at the upper

part of the upright wall 57 of the recess to brace the flange 53 and to prevent distortion of the socket base and shoulder. The upstanding cylindrical wall 57 surrounding the outermost part of the ring-holding recess 58 is in turn braced by the conical flange 53 against outward movement under stress.

In all of the forms of the invention, it will be seen that a two piece resilient socket is provided in which the various walls of the socket forming members are so bent as either to double the thickness of the material at the areas where the greatest stresses occur, or to arrange the walls in mutually bracing relation for added strength with the employment of a minimum amount and thickness of material, and that there is provided a socket well adapted for economical manufacture and practical use.

Various changes may obviously be made in those specific forms of the invention which have been shown and described as illustrative within the scope of the appended claims.

I claim:

1. A two-piece resilient socket comprising a first member of a single piece of material having a base and having a part extending from the base and constituting two rigid and mutually perpendicular sides of a channel shaped three-sided ring-holding recess, a resilient ring in and inwardly overhanging the recess, the base being doubled back on itself at its inner periphery to provide two adjacent thicknesses of material at the bottom of the recess, and a second member having a spreadable eyelet part and having a right angle bend at an end of said eyelet part to form a rigid shoulder adjacent the top of the recess parallel to the bottom of the recess and in contact with the extreme top end portion of the other of said two sides of the recess, said second member having an outstanding base secured to and reinforcing the base of the first member.

2. In a resilient socket, a pair of members arranged in mutually reinforcing relation and each having a plurality of spaced apart bends therein to form a ring-holding three-sided recess and a resilient ring in and inwardly overhanging the inner edge of the recess, one of said members having an eyelet portion terminating in an annular horizontal rigid shoulder constituting the top of the recess, the other of said members having a rigid cylindrical wall of uniform diameter bounding the outermost side of the recess and having an extreme top end part in contact with the shoulders, said other member having a doubled over portion extending inwardly from the lower edge of and perpendicular to the wall forming the bottom side of the recess and having a rounded inner edge surrounding a stud entrance opening therein, each of said members having a base portion secured to and in contact with the base portion of the other member.

3. In a resilient socket, a pair of members arranged in mutually reinforcing relation and to form a three-sided rigid ring-holding recess, and a resilient ring in the recess, one of said members having an eyelet portion terminating in an outstanding rigid shoulder adjacent the top of the recess, the other member having a rigid cylindrical wall constituting the outermost side of the recess and in contact at its extreme upper end with and perpendicular to the shoulder, said other member having a portion of double thickness extending inwardly and perpendicularly from the wall substantially parallel to the shoulder and forming the

bottom wall of the recess, the innermost edge of said last mentioned portion being rounded.

4. In a resilient socket, an eyelet member having part thereof in position to form a base and another part in position to form at least one rigid cylindrical side wall of a channel-shaped ring-holding recess, a resilient wire ring in and projecting inwardly beyond the recess, and a second member having a base secured to the base of the eyelet member, the base of the second member having a bend at its inner periphery to provide a bottom wall of the recess perpendicular to said side wall and of two thicknesses of material, said second member having a cylindrical wall extending upwardly from said bend and in contact with the inner face of said one side wall of the recess.

5. In a resilient socket, an eyelet member provided with an outstanding substantially horizontal shoulder and a base, and a second member having a rigid upstanding cylindrical wall of uniform diameter, the top of said wall engaging the under face of the outer periphery of the shoulder and an inwardly extending rigid flange of two thicknesses of material at an end edge of and substantially perpendicular to the wall and in substantially parallel spaced relation to the shoulder to form a channel-shaped ring-holding recess between the shoulder, the flange and the wall, the shoulder constituting the top of the recess, the flange constituting the bottom of the recess, and the wall constituting the outer side of the recess, the recess being open at its inner side, a resilient ring in the recess, and a base on the second member secured to the base of the eyelet member, the innermost edges of the shoulder and of the flange being of substantially the same diameter.

6. In a two piece resilient socket of the type adapted to be clinched to a sheet by a cooperating anvil-carrying cap, an eyelet member comprising an upstanding cylindrical eyelet part terminating at its lower end in a substantially flat outstanding shoulder, a cylindrical wall depending from the outer periphery of the shoulder and terminating at its lower end in a substantially flat outstanding base, said wall being of uniform diameter throughout the height thereof, and a second member surrounding the major part of a channel-shaped recess for the reception of a ring, said second member having a substantially flat base in contact with the base of the eyelet member, a rim on the base of the second member inwardly overhanging the periphery of the base of the eyelet member, a substantially 180° bend at the inner periphery of the base of the second member doubling said base back on itself to form two contacting thicknesses of material perpendicular to the wall and constituting the bottom of the recess, a second cylindrical wall upstanding from the upper of said two thicknesses and in contact with the inner surface of the depending wall of the eyelet member to provide two thicknesses of material at the outer side of the recess, said second wall touching the under face of the shoulder, said shoulder constituting the

65

top of the recess, and a resilient wire ring in the recess and inwardly overhanging the shoulder and the 180° bend.

7. A ring-holding socket consisting only of two pieces of sheet material and an open ring of round wire, one of said pieces comprising a rigid, unyielding, upright, continuous and uninterrupted cylindrical wall forming the outer side of an annular channel-shaped recess in the socket and also forming the inner of two thicknesses at said outer side, the inner diameter of the wall being uniform throughout the height thereof, said height being greater than the diameter of the wire of said ring, the recess being open at the side opposite said wall, a flat annular continuous and uninterrupted shoulder extending inwardly from the lower end of the wall and integrally joined thereto by a rigid continuous and uninterrupted 90° bend, said shoulder forming the lowermost side of the recess and being of lesser width than the diameter of the wire of said open ring, the ring being arranged in the recess to overhang inwardly over the innermost edge of said shoulder, a bend subtending approximately 180° at the innermost edge of the shoulder, said bend continuing outwardly in the form of an annular flange having its innermost peripheral part in contact with the under face of said shoulder and providing the lower of two thicknesses of material along the bottom of the recess, the other of said two pieces comprising a second upright rigid cylindrical wall in contact with the outer surface of the first mentioned wall and thereby providing two thicknesses of material throughout the outer side of the recess, a substantially right angle bend at the top of the second wall and integrally joining the second wall to a second horizontal inwardly extending shoulder forming the top of the recess and in contact with the upper edge of the first mentioned wall, a second substantially right angled bend at the inner edge of the second shoulder joining said shoulder to an eyelet, and a bend at the lower edge of said second wall joining said wall to a second outstanding annular flange in contact with the upper face of the flange of the first mentioned one of said pieces, and a rim on the outer edge of said first mentioned piece having a bend extending past the periphery of the second flange and in contact with the upper face of the second flange.
